TAMPERPROOF CLOSURE SEAL

Solomon Grauer, Brooklyn, N. Y.

Application April 20, 1935, Serial No. 17,402

9 Claims. (Cl. 215—7)

The invention relates to tamper-proof seals of the type which when once placed on a bottle, or other container, cannot be removed therefrom without breaking the bottle or container. It has 5 for its main object to provide a seal which may be used in connection with various kinds of stoppers or closure devices and which will immediately indicate the initial opening of such. Another object is to so construct the seal that it 10 may be used in connection with non-refillable bottle stoppers to effectively prevent their removal from the bottles, which is one of the most serious disadvantages of most non-refillable stoppers now on the market. A further object is to provide a 15 device which may be manufactured and secured on a bottle at a very low cost and with a minimum expenditure of labor, and which will not materially add to the size of the bottle nor detract from its appearance.

20 These and various other objects and advantages will be readily understood from the following description and from the accompanying drawings of preferred embodiments of the invention, in which, however, modifications may be made without departing from the scope of the appended claims.

In the drawings

Fig. 1 is a side view, shown partly in cross-section, of the neck of a bottle to which the invention has been applied;

30 Fig. 2 is another side view;

Fig. 3 is a similar side view with the seal and the closure cap removed to show the construction of the bottle neck;

Fig. 4 is a top view of Fig. 1;

35 Fig. 5 is a side view of the closure seal;

Fig. 6 is a top view of Fig. 3;

Fig. 7 is a top view of a slightly modified seal;

Fig. 8 is a cross-sectional side view of another slight modification of the seal;

40 Fig. 9 is a bottom view of Fig. 7;

Fig. 10 is a side view of another modification of the seal;

Fig. 11 is a top view of Fig. 10;

45 Fig. 12 is a side view of a bottle neck containing a seal as used in connection with non-refillable bottle stoppers;

Fig. 13 is a cross-sectional side elevation of the bottle neck shown in Fig. 12;

50 Fig. 14 is a cross-sectional side elevation of Fig. 12 but with a closure cap added;

Fig. 15 is a top view of Fig. 14;

Fig. 16 is a top view of Fig. 12;

Fig. 17 is a top view of Fig. 13;

55 Fig. 18 is a side view of the closure cap shown in Fig. 12;

Fig. 19 is a side view of a bottle neck with a closure seal of a slightly modified construction;

Fig. 20 is a top view of Fig. 19; and

Fig. 21 is a top view of a seal slightly modified from that shown in Figs. 19 and 20.

5 Referring first to Figs. 1 to 9, in which the bottle neck is shown at 10, a closure cap at 11 and the seal at 12, the upper part of the bottle neck is provided with a thread 13 on which the closure cap fits. The seal is of tubular shape 10 with an inwardly extending flange 14 formed at its top and has a plurality of cut-out portions 15, as plainly shown in Fig. 5. An arm 16 is connected to the flange 14 by a weakened portion 17. The arm extends upwardly and inwardly 15 over the cap and terminates in a finger grip 18, as plainly shown in Fig. 1.

The bottle neck 10, as shown in Figs. 3 and 6, is provided with a plurality of grooves 19. The seal 12 is inserted over the shoulder 20 in such 20 a manner that the cut-out portions 15 fit over a plurality of projections 21 formed in the bottle neck. After the seal has been placed over the shoulder 20, the lower edges of the seal are pressed into the grooves 19 to form hooks 22 which engage against the upper part of the grooves. These hooks are plainly shown in Figs. 1, 5, 7 and 9. While I prefer to form the hooks after the seal has been placed on the bottle, in some cases I find it advantageous to form the hooks first and 30 then snap the seal over the bottle neck. When this is done a plurality of slots 23 are preferably formed in the seal to make it more yielding.

It would be seen that, when the seal has been placed on the bottle, the cap 11 cannot be removed without bending the arm 16. As the arm is weakened at 17, this bending will cause it to break off and thus show that the cap has been removed from the bottle. Inasmuch as the seal is completely embedded in the glass of the bottle 40 neck, it is impossible to pry the seal off and to substitute another. Thus any initial opening of the bottle is plainly indicated. When slots, such as shown at 23 are employed, ridges of glass may be moulded on the bottle neck to extend into these 45 slots.

In Figs. 7 and 9 the seal is shown with two arms, but it is evident that any number of arms may be employed. In Fig. 8, which is particularly suitable for a bottle in which an ordinary cork 50 stopper is employed, the arm 24 does not extend upwardly but is merely bent inwardly so as to engage with the top of the cork. In Figs. 10 and 11 semi-circular shields 25 and 26 have been substituted for the arms. These shields are only 55

connected to the seal by the narrow portions 27 and are provided with finger grips 28 to facilitate bending them sidewardly. The shields fit over the whole cap 11 and must be broken off before it can be removed.

Reference is now had to Figs. 12 to 18, inclusive. The bottle neck 29 is provided with a plurality of grooves 30, as in the previous cases, and the seal 31 is provided with hooks 32 which engage in these grooves. Projections 33 fit in the cut-out portions 34, but in this case a thread 35 is formed on the projections. The seal now being described is particularly well adapted for securing non-refillable bottle stoppers, such as the one shown at 36, in the neck of a bottle.

The stopper is inserted in the bottle in the usual manner and a gasket 37 is placed on top of the bottle and underneath the flange 38 of the stopper. The seal has no arm, but the flange 39 is provided with a downwardly extending rim 40 which engages the flange 38 and imparts resiliency to the seal and clamps the stopper in the bottle after the hooks 32 have been bent into the grooves 30. An internally threaded cap 41 may be placed on the thread 35 and a gasket 42 is preferably placed inside of the cap for engagement with the top of the seal.

In the embodiment shown in Figs. 19 and 20 the projections 33 carry no thread and a substantially circular arm 43 is formed on the seal and connected to it by the narrow portion 44, plainly shown in Fig. 20. The arm is provided with a finger grip 45 and engages on a cork gasket 46 which closes the outlet opening 47 in the non-refillable stopper 36. The seal shown in Fig. 21 is provided with two semi-circular arms 48 and 49 which are connected to the seal by narrow portions 50 and 51. It is provided with finger grips 52 and 53, and arms engage the gasket 46. It will be seen that before the gasket can be removed so that the contents can be poured from the bottle, the arms 43, or 50 and 51, as the case may be, must be broken off.

From the foregoing it will be seen that the seal is of simple and inexpensive construction and that it cannot be removed from the bottle when once attached thereto. While I have described the various seals in combination with bottles only, it is evident that similar seals might be employed on various other containers where such seals might be desirable or advantageous. Likewise, while I have described and illustrated one embodiment of the seal for use with a non-refillable bottle stopper, it is evident that this embodiment may also be used for permanently securing other stoppers in bottles, as for example, stoppers used for sprinkling hair tonics, perfumes and the like.

Having described the invention and its objects, what I claim as new and wish to protect by Letters Patent is:

1. A device of the class described comprising a tubular seal attachable over the discharge end of a container, an inwardly extending flange formed at the upper end of the seal, a plurality of cut-out portions formed in the other end of the seal and adapted to accommodate a plurality of projections provided on the container, inwardly extending hooks formed on the end of the seal which when engaged in grooves provided in the container secure the seal to the container and permanently prevent its removal therefrom, and a plurality of arms connected to said flange and extending inwardly over and engaging the closure of the container, and the connections between

the arms and the flange weakened to facilitate breaking said connections.

2. A device of the class described comprising a tubular seal attachable over the discharge end of a container, an inwardly extending flange formed at the upper end of the seal, a plurality of cut-out portions formed in the other end of the seal and adapted to accommodate a plurality of projections provided on the container, inwardly extending hooks formed on the end of the seal for permanent engagement in grooves provided in the container, a pair of semi-circular shields connected to said seal and extending inwardly from said flange to cover the closure of the container, and the connections between the shields and the seal weakened to facilitate breaking said connections.

3. In combination; a container having a plurality of radial projections around its discharge opening and grooves between said projections and some distance below the discharge opening; a stopper inserted in the discharge opening and having an outwardly extending flange; and a tubular seal attachable over the discharge end of the container, said seal having an inwardly extending flange engageable on the flange of the stopper, a plurality of cut-out portions for accommodating the projection on the container, and a plurality of hooks on its lower end which when engaged in the grooves in the container secure the seal to the container and permanently prevent its removal therefrom.

4. In combination; a container having a plurality of radial projections around its discharge opening and grooves between said projections and some distance below the discharge opening; a stopper inserted in the discharge opening and having an outwardly extending flange; a tubular seal attachable over the discharge end of the container, said seal having an inwardly extending flange engageable on the flange of the stopper, a plurality of cut-out portions for accommodating the projections on the container, a plurality of hooks on its lower end which when engaged in the grooves in the container secure the seal to the container and permanently prevent its removal therefrom, and the said projections provided with external threads; and an internally threaded cap secured on said threads.

5. In combination; a container having an external thread around its discharge opening, an enlargement below said thread, a plurality of radial projections on said enlargement, and grooves between and at the lower ends of said projections; a closure cap secured on the thread; and a tubular seal secured on the container and having an inwardly extending flange formed on the upper end of and engaged against the upper end of the enlargement on the container, a plurality of cut-out portions for accommodating the projections on the enlargement, a plurality of hooks on its lower end which when engaged in the grooves in the enlargement secure the seal to the container and permanently prevent its removal therefrom, an upwardly and inwardly extending arm for engaging the top of the closure cap, and the connection between the arm and the seal weakened to facilitate breaking the connection.

6. In combination; a container having an external thread around its discharge opening, an enlargement below said thread, and grooves some distance below the top of said enlargement; a closure cap secured on the thread; and a tubular seal secured on the container and having an in-

wardly extending flange formed on the upper end of and engaged against the upper end of the enlargement on the container, a plurality of hooks on its lower end which when engaged in the 5 grooves in the enlargement secure the seal to the container and permanently prevent its removal therefrom, an upwardly and inwardly extending arm for engaging the top of the closure cap, and the connection between the arm and the seal 10 weakened to facilitate breaking the connection.

7. In combination; a container having an external thread around its discharge opening, an enlargement below said thread, a plurality of radial projections on said enlargement, and 15 grooves between and at the lower ends of said projections; a closure cap secured on the thread; and a tubular seal secured on the container and having an inwardly extending flange formed on the upper end of and engaged against the upper 20 end of the enlargement on the container, a plurality of cut-out portions for accommodating the projections on the enlargement, a plurality of hooks on its lower end which when engaged in the grooves in the enlargement secure the seal to the container and permanently prevent its removal 25 therefrom, a plurality of upwardly and inwardly extending arms for engaging the top of the closure cap, and the connections between the arms and the seal weakened to facilitate breaking the 30 connections.

8. In combination; a container having an ex-

ternal thread around its discharge opening, an enlargement below said thread, a plurality of radial projections on said enlargement, and grooves between and at the lower ends of said projections; a closure cap secured on the thread; and a tubular seal secured on the container and having an inwardly extending flange formed on the upper end of and engaged against the upper end of the enlargement on the container, a plurality of cut-out portions for accommodating the projections 10 on the enlargement, a plurality of hooks on its lower end which when engaged in the grooves in the enlargement secure the seal to the container and permanently prevent its removal therefrom, upwardly extending shields for covering the closure 15 cap, and the connections between the shields and the seal weakened to facilitate breaking the connections.

9. A device of the class described comprising a tubular seal attachable over the discharge 20 end of a container, an inwardly extending flange formed at the upper end of the seal, the lower end of the seal adapted to be bent into a groove provided in the container on which a seal is used for permanent engagement with said container, 25 a pair of semi-circular shields connected to said seal and extending inwardly from said flange to cover the closure device of the container, and the connections between the shield and the seal weakened to facilitate breaking said connections. 30

SOLOMON GRAUER.
